UNITED STATES PATENT OFFICE.

LESLY R. TUFTS, OF CLEVELAND, OHIO, ASSIGNEE TO THE CLEVELAND FOLDING MACHINE COMPANY, OF CLEVELAND, OHIO, A CORPORATION OF OHIO.

PAPER DEFLECTOR.

Application filed December 22, 1924 Serial No. 757,349.

My invention relates to improvements in paper deflectors and has for its object the provision of means preferably associated with continuous sheet-feeding mechanism, whereby the sheets of paper will be supplied to the feed table and feeding rolls in evenly displaced or fanned-out arrangement for presentation to said rolls; and more particularly to the provision of means adapted for handling relatively short sheets of paper.

Continuous feeding mechanism of the type to which my improvements are herein applied, by way of example, affords two levels, usually comprising feeding belts traveling over feeding tables arranged one above the other, whereon said belts travel in reverse direction. The upper level or table is supplied by the attendant with the sheets of paper fanned-out forwardly from the bottom to the top of the pile and suitable deflector means are provided for reversing the arrangement of the fanned-out sheets and properly positioning them upon the lower table.

Hitherto certain difficulty has been experienced in adapting deflector mechanism for operation with sheets of varying length and, more especially, with the shorter sheets of paper which not infrequently would slip forwardly or out of alinement as the superposed sheets were leaving the deflector mechanism. Quite obviously such slippage interferes with the operation of the associated paper-feeding and handling mechanism.

Accordingly, I have supplied suitably spring-tensioned resilient members in the deflector mechanism of this type, whereby the sheets are retained in proper relation and are uninterruptedly delivered in alinement to the lower feed table.

The features of my improved construction may be more readily explained in connection with the accompanying drawings illustrating a preferred embodiment thereof, wherein:

Figure 1 is a side view of a two-level continuous sheet-feeding mechanism to which my improvements have been adapted and applied.

Fig. 2 is an interrupted plan view thereof on the irregular line 2--2, Fig. 1, the left-hand portion of the upper feed table being broken away,

Fig. 3 is an enlarged fragmentary view in

vertical section illustrating my improved sheet deflector upon an enlarged scale, with a pile of fanned-out sheets in transit therethrough, and

Fig. 4 is a similar view thereof showing a pile of fanned-out sheets about to be entered within said deflector.

Throughout the several figures of the drawings I have employed the same character of reference to indicate similar parts.

Reference may initially be made to Figures 1 and 2, from which it will be observed that the sheet-feeding mechanism comprises an upper feeding table *a* superposed at a slight angle above the lower feeding table *b*; said feeding tables respectively being equipped with sets of traveling belts *a'*, *b'*, whereon the sheets are conveyed respectively in reverse directions. Lateral guides *a''*, *b''* are adjustably mounted in position to direct the sheets in alinement toward the deflector mechanism upon the right of the machine, and again, toward the feeding rolls upon the left of the apparatus herein shown.

It may be observed at this point that preferably the sheets are supplied to and throughout the continuous feeding mechanism in a substantially continuous or uninterrupted thickness of superposed fanned-out sheets of paper, as nearly as may be, extending from a position rearwardly or to the left of the deflector mechanism and along the lower feeding table *b* to the rolls *c*, *c'* at the left. However, for the purpose of present illustration and description I have shown merely two bundles or sections of superposed sheets *d*, *d'*, suitably fanned-out respectively upon the upper and lower feeding tables. The former, *d*, is manually disposed upon the table *a* and the conveyor belts *a'*, and is properly fanned-out by the operative for passing through the deflector mechanism, as indicated in Fig. 3, while the latter section, *d'*, exhibits the reverse arrangement of the sheets after passing through the deflector, adapting them for the action of the feeding rolls *c*, *c'*. In this arrangement the forward edges of the sheets overlie and extend beyond the forward edges of those beneath them in the particular group or section, and, in practice, this mode of superposition is maintained as nearly continuous as possible in order to expedite operations and increase production.

- The particular mechanism for effecting the deflection and reversal of the sheet arrangement may now be explained by making reference to Figures 3 and 4; in the latter 5 of which the edges of the fanned-out sheets *d* are shown forwardly advancing beneath the curved resilient members *e* that are adjustably mounted along the rod *e'* to conform with the particular width of paper in 10 progress through the deflector, and, generally, with the contour of the preferred thickness of the section of sheets as it is passing around the cylinder *f* of the deflector, as shown in Fig. 3.
- 15 In order to adapt the deflector mechanism for use with sheets of paper of radically different lengths, and more particularly, relatively short sheets, I have provided a second series of curved resilient members *g* adjustably mounted along the rod *g'* and tensioned to react against the cylinder and superposed paper by means of the adjustable spring *g''*. These members *g* are in 20 staggered and overlapping relation with respect to the resilient members *e*, whereby the sheets are maintained within the embrace of the upper and lower resilient members throughout approximately 180° circumferentially of the cylinder *f*.
- 25 Accordingly, the reversed sections of sheets are maintained in their relative fanned-out relation and in alinement as the same are transferred to the traveling belts *b'* of the lower feeding table, along and 30 with which said sheets are conveyed toward and between the feeding rolls *c*, *c'*, for transfer to folding or printing apparatus, for example, not shown herein. The details of the auxiliary mechanism do not require 35 further description or illustration to make clear the construction and purpose of my instant improvements.
- An important advantage attainable by 40 the use of upper and lower resilient members, particularly when short sheets of paper are being handled in the machine, is found in the retention of such sheets by the upper series of members until they are well within the embrace of the lower series of resilient 45 members. Moreover, since the lower resilient members have their independent tensioning means, these members will not release a stack of short sheets when a thicker 50 stack is entered at the upper portion of the reversing cylinder; an undesirable result not infrequently occurring when a single series 55 of retaining members is relied upon in this type of machine for maintaining the relative arrangement of the reversed sheets.
- 60 It has been found that with the construction shown sheets of any workable length may be handled through the proper adjustment of the closely embracing sets of resilient members provided for the deflector mechanism.

Having now described the preferred embodiment of my invention and its manner of use, I claim as new and desire to secure by Letters Patent, the following:

1. In apparatus of the class described, the 70 combination with means for conveying and reversing the arrangement of sheets of paper, of upper and lower sets of resilient members associated with said means and adapted to bear upon and maintain the relative arrangement of the sheets throughout their course of reversal in said apparatus, and independent tensioning means for both sets of resilient members, substantially as set forth.
2. In apparatus of the class described, the 75 combination with a rotatable reversing cylinder, of upper and lower sets of resilient members associated therewith and adapted to bear peripherally upon the cylinder and 80 any superposed sheets throughout the course of the latter during reversal and release of the sheets, and independent tensioning means for both sets of resilient members, substantially as set forth.
3. In apparatus of the class described, the 85 combination with substantially superposed feeding tables, of a reversing cylinder interposed between said feeding tables, a plurality of resilient members engaging the lower portion of the cylinder, and spring-actuated means for holding said resilient members in 90 position to retain the arrangement of the sheets, substantially as set forth.
4. In apparatus of the class described, the 95 combination with a rotatable reversing cylinder, of upper and lower sets of adjustable resilient members arranged in terminally overlapping relation about the cylinder, independent tensioning means respectively associated with both sets of resilient members, and means for securing their adjustment, 100 substantially as set forth.
5. In apparatus of the class described, the 105 combination with a reversing cylinder, of means for conveying sheets peripherally thereof, and adjustable resilient members positioned in independent sets above and below but adjacent to said cylinder approximately embracing it for 180° and adapted to 110 retain the relative arrangement of the sheets during reversal and delivery, substantially as set forth.
6. In apparatus of the class described, the 115 combination with two feeding tables, of reversing means interposed therebetween, and a plurality of adjustable resilient members associated with said means and positioned below and rearwardly of said reversing means to direct the sheets immediately upon the second feeding table in unaltered but reversed arrangement, substantially as set forth.
7. In apparatus of the class described, the 120 combination with a reversing cylinder, of 125

means for conforming the sheets to the upper curvature of said cylinder, and a series of tensioned resilient members positioned adjacent to the lower surface of said cylinder and adapted independently to retain the relative arrangement of the sheets until their reversal and delivery have been completed, substantially as set forth.

8. In apparatus of the class described, the combination with a reversing cylinder, of

means for conveying sheets peripherally thereof, and coating upper and lower sets of resilient members positioned adjacent to said cylinder; said lower set being independently tensioned and adapted to retain the relative arrangement of short sheets until their delivery, substantially as set forth. 15

In testimony whereof I do now affix my signature this 17th day of December, 1924.

LESLEY R. TUFTS.
